UNITED STATES PATENT OFFICE.

FREDERICK CHARLES TILLEY, OF HENDON, LONDON, ENGLAND.

HYDROCARBON-VAPOR BURNER.

Application filed April 23, 1927, Serial No. 186,104, and in Great Britain May 25, 1928.

This invention relates to that class of hydrocarbon vapor burner having a vaporizing tube and its appendages fitted with a reciprocable needle for cleaning the jet orifice and in which the supply of liquid fuel to the vaporizing tube shall be cut off when the jet orifice at the end of the vaporizing tube is closed by the needle or vice versa.

The object of the present invention is to construct in an improved manner the appliances for cutting off the supply of petroleum or liquid fuel to the vaporizing tube when the point of the needle has entered the small orifice at the end of the vaporizing tube to close same and vice versa, and whereby should any excess of pressure be set up in the vaporizing tube it will act upon the closure valve and open it so that the excess of pressure will pass to the container.

20 My invention will be readily understood from the construction shown on the annexed drawings in which:—

Figure 1 is an elevation of a lamp of the kind in which my invention can be applied.

25 Figure 2 is a sectional elevation of a suitable form of vaporizing tube, needle and operating mechanism with my invention applied.

Figure 3 is a section on the line *a—a* of Figure 2.

30 Figure 4 is a section on the line *b—b* of Figure 2.

Figure 5 is a section on the line *c—c* of Figure 2.

35 According to this invention the entrance end of the fitting *D* is reduced in internal diameter and provided with a portion *D¹* of smaller external diameter, projecting from the fitting *D* with the end formed as a valve seating 6.

40 Within the fitting *D* is positioned a rod 7 having flutings *7^a* and a mushroom head *7^b* and normally one end projects beyond the fitting whilst the mushroom head *7^b* engages the eccentric *N*.

45 Screwed to the extension *D¹* is a tube 8 having one end perforated, as at 9, and within the tube is a valve 10 guided by a stem 11 in a central perforation of the end of the tube 8 and controlled by a coiled spring 12 encircling the stem 11 to normally press the valve 10 on the seating 6 at the end of the extension *D¹*.

50 The tube 8 and its appendages are preferably situate within the container *E* or it may be a supply pipe.

The eccentric mechanism *N* operated by the turn button *Q* is employed for actuating the needle *J* in one direction, a spring *L* actuating the needle *J* in the other, and the rod 7 is of such a length that when the eccentric *N* is in one position and the needle *J* withdrawn from the jet orifice *O*, the rod 7 can act upon the valve 10 and move it from its seating 6 as at Figure 2.

55 The rod 7 loosely fits the fitting *D* so that oil can pass up the flutings *7^a* to the vaporizing tube *A*, and the valve 10 in the tube 8 is also a loose fit for the same purpose, the oil under pressure passing through the perforations 9 in the tube 8 around the valve 10 and rod 7 and up the flutings *7^a* to the vaporizing tube *A*.

60 In use when the turn button *Q* has been actuated to lift the needle *J* to close the jet orifice *O*, the eccentric *N* has freed itself from the rod 7 and the spring 12 has closed the valve 10 on to the seating 6 and stopped the supply of liquid fuel to the vaporizing tube *A*, and on a reversal of the eccentric *N* the 65 needle *J* is freed from the jet orifice and the eccentric *N* has acted upon the rod 7 and forced the valve 10 from its seating to allow liquid fuel to pass to the vaporizing tube.

65 I prefer to mount a filter bag 13 on the perforated tube 8.

70 By this invention should any excess of pressure be set up in the vaporizing tube it will act upon the valve 10 to open same and allow the excess vapor to pass to the container.

75 Although my invention is described as in connection with a lamp it can be applied when the vaporizing tube is used for burners 80 other than lighting.

85 What I do claim as my invention and desire to secure by Letters Patent is:—

1. The combination with a hydrocarbon fuel supply, of a burner including a vaporizing tube having a jet orifice, a spring-opened jet valve, a spring-closed fuel control valve, manually operated means for closing the jet valve and permitting the fuel valve to close, and means for directing the excess gas pressure in the tube to automatically open the fuel valve so that such excess gas will pass into the fuel supply.

100 2. The combination with a hydrocarbon fuel supply, of a burner including a vaporizing tube having a jet orifice, a spring-opened jet valve, a spring-closed fuel control valve,

a grooved rod normally engaging the fuel valve, and manually controlled means for depressing said rod to open the fuel valve and permitting the jet valve to open and for closing the jet valve and permitting the fuel valve to close, and whereby any excess pressure in the tube will pass around the rod to open the fuel valve to exhaust into the supply.

10 3. The combination with a hydrocarbon fuel supply, of a burner including a vaporizing tube having a jet orifice, a spring-opened jet valve, a spring-closed fuel control valve, a manually operable eccentric for controlling the valves, the jet valve when closed by the eccentric permitting the fuel valve to also close, and means whereby, when the pressure in the vapor tube overcomes that in the fuel supply, the fuel controlled valve is opened.

15 4. The combination with a hydrocarbon fuel supply, of a burner including a main carrying body, a vaporizing tube having a jet orifice at the upper end thereof, a spring-opened needle valve for controlling said orifice, a spring-closed fuel control valve at the lower end of the main body, manually controlled means interposed between the two valves, whereby when the jet valve is closed the fuel valve is also closed, and means when 20 both valves are closed and the pressure in the vaporizing tube is greater than that in the fuel tank, the fuel valve will be opened to admit the gas to the tank.

30 5. A burner including a main casing provided with a valve seat in its lower end, a vaporizing tube having a jet orifice at the other end of the casing, a spring-opened valve for the jet orifice mounted in the casing, a spring-closed fuel valve at the lower end of the casing and normally engaging the seat, and a manually controlled eccentric mounted in the casing for operating the valves.

35 6. A burner including a main casing provided with a valve seat in its lower end, a vaporizing tube having a jet orifice at the other end of the casing, a spring-opened valve for the jet orifice mounted in the casing, a spring-closed fuel valve at the lower end of the casing and normally engaging the seat, and a manually controlled eccentric mounted in the casing for operating the valves, the orifice valve being closed when the fuel valve is closed and the spring of the latter valve being of such strength as to

permit the valve to unseat due to excess pressure in the vaporizing tube.

7. A burner including a main casing provided with a valve seat in its lower end, a vaporizing tube in the upper end and provided with a jet orifice, a spring-opened valve for the orifice mounted in the casing, a spring-closed fuel valve at the lower end of the casing and normally engaging the seat, a grooved rod slidably mounted in the casing and normally engaging the fuel valve, and a manually controlled eccentric disposed between said rod and the jet valve whereby, when the jet valve is closed, the fuel valve is also closed.

8. A burner including a main casing provided with a valve seat in its lower end, a vaporizing tube in the upper end and provided with a jet orifice, a spring-opened valve for the orifice mounted in the casing, a spring-closed fuel valve at the lower end of the casing and normally engaging the seat, a grooved rod slidably mounted in the casing and normally engaging the fuel valve, and a manually controlled eccentric disposed between said rod and the jet valve whereby, when the jet valve is closed, the fuel valve is also closed, the spring of the fuel valve being of such a tension that when the pressure in the vaporizing tube is of sufficient strength it will open the valve and permit the escape of such pressure through the fuel valve.

9. The combination with a fuel tank, of a burner connected thereto and having two spring-actuated valves, one of the valves being normally opened and the other normally closed, and selective means for closing the normally-opened valve and for opening the normally closed valve.

10. The combination with a fuel tank, of a burner connected thereto and having two spring-actuated valves, one of the valves being normally opened and the other normally closed, a vaporizing tube having a jet orifice, the spring-opened valve being disposed to control the orifice, and selective means for closing the latter valve and permitting the other valve to close, the tension of the spring of the last-mentioned valve being such that any excess pressure in the vaporizing tube will open said valve.

In testimony whereof I have hereunto set my hand.

FREDERICK CHARLES TILLEY.
